CONTAINER

Percy H. Waller, Wilmette, and Edward B. Nottingham, Villa Park, Ill., assignors, by mesne assignments, of one-half to said Waller and one-half to Charles C. Kirk, both of Chicago, Ill.

Application February 17, 1943, Serial No. 476,132

4 Claims. (Cl. 217—44)

The present invention relates to the construction of containers and particularly to containers which are adapted for heavy duty use either in transportation or in the field for delivering such materials as fuel oil.

It is the principal purpose of this invention to provide a device of this character which is of a knock-down construction that can be filled with the liquid to be transported and transported while filled and then broken down into its component parts for ready shipment on a return trip in a limited amount of space.

The invention further contemplates a container having the characteristics above described which is protected at its ends by heavy bulkheads that can serve as supports for the container to enable it to be rolled along a surface, the bulkheads themselves being separable in a simple fashion from the rest of the container to permit ready dismantling of the container.

It is also a purpose of this invention to provide a device of this character wherein adjustments to allow for shrinkage can be made at all times so that variations in weather conditions to which the container is subjected will not result in destruction of the container or leakage of its contents.

The features and advantages of the present invention will appear more fully as the description proceeds, reference being had to the accompanying drawings wherein a preferred form of the invention is shown. It should be understood however that the drawings and description are illustrative only and are not to be taken as limiting the invention except insofar as it is limited by the claims.

In the drawings:

Fig. 1 is a view in side elevation of a container embodying the invention;

Fig. 2 is a sectional view taken substantially on the line 2—2 of Fig. 1;

Fig. 3 is an enlarged fragmentary section taken substantially on the line 3—3 of Fig. 2;

Fig. 4 is a fragmentary sectional view taken on the line 4—4 of Fig. 3;

Fig. 5 is a partial perspective view of the bulkhead separate from the rest of the container;

Fig. 6 is a perspective view of a channel section which is a part of the construction; and

Fig. 7 is a perspective view of a bolt lug which is used in coupling the bulkhead to the body of the container.

Referring now in detail to the drawings, the present invention is embodied in a container consisting of a polygonal body portion 10 and two

bulkheads or ends 11 and 12. The construction as shown comprises an octagonal body portion wherein a plurality of substantially like panels 13 are joined by channel elements 14. Each channel element comprises two oppositely directed channel portions 15 and 16 (see Fig. 6) which are angularly disposed with respect to each other. The channels terminate a short distance from the ends of the panels 13 leaving the panels 10 protruding as indicated at 17 in Fig. 3. The bulkheads 11 and 12 fit over the protruding portion 17 of the panels so as to effect an enclosure. The container is made liquid-tight by lining it with a bag or other form of lining which is impervious to the liquid being transported. This lining may be applied in bag form or it may be applied by the simple expedient of spraying a quick setting material on the inner surface of the container after it is set up and before the final bulkhead is applied thereto. In the latter event it will of course be necessary in dismantling the container to destroy the lining at the joints where the panels meet the bulkheads and where they fit into the channels. However, upon the 25 next assembly of the container it can be rendered liquid proof by merely spraying the joints with the liquid impervious material.

Referring now in detail to the construction as illustrated best in Figs. 3 to 7, inclusive, it will be noted that the channel members 14 at their ends are provided with apertures 18 and 19. These apertures are placed in both walls 20 and 21 of the U-shaped portion of an outer strip 22 which forms a part of the channel member 14. The outer strip 22 is riveted or welded to an inner strip 23 which cooperates with the strip 22 to provide the two channels 15 and 16. Details of this construction are shown and claimed in an application Serial No. 476,036, filed by us on the 16th day of February, 1943. The purpose of the openings 18 and 19 is to receive locking pins 24 (see Figs. 3 and 4) by which a U-shaped bolt lug 25 is attached to the channel member 14. The bolt lug comprises a strip of sheet metal 45 bent into the form shown in Fig. 7 and provided with openings 26 to receive the pins 24. In assembling a container the bolt lugs are attached by means of the pins 24 to a channel and then two adjacent panels 13 are inserted in the channels 15 and 16. Preferably the assembly is carried out in one of the bulkheads as a base and additional channels and panels can be added after the first two panels are in place until a complete ring is made. The pins 24 of course cannot escape when the panels are in place and once

the complete ring is formed suitable bind straps 27 and 28 are placed around the panels and drawn taut by means of turnbuckles 29 and 30.

It will be noted that the bulkheads 11 and 12 are made up of a flat disk 31 and a ring 32, the inner surface being cut out to conform to the shapes of the panels 13, that is, to an octagonal shape. We find that it is desirable to construct the bulkhead disk 31 of a strong material such as plywood and the ring 32 preferably is made of hard wood such as maple so as to withstand the rough usage as a rolling surface and supporting surface for the weight of the container when it is full of liquid. Additional rings may, if desired, be placed between the ends of the panels to serve as a supporting means. When this is done the ring is made in sections and the sections are united by overlapping joints.

The final step in the assembly is to insert bolts 33 through the disks 31, the rings 32 and the lugs 25 and draw these bolts up by means of nuts 34 until the bulkhead is forced against the ends of the panels. Before placing one of the bulkheads in position a lining 35 is provided on the interior of the container. Where the lining is in the nature of a bag it is brought up to the end of the panels and lapped over the ends of the panels so as to be caught between the bulkhead to be applied and the ends of the panels. The same procedure roughly is utilized when the lining is sprayed on the interior of the container. In such instances a thick, quick hardening, liquid impervious material such as a vinyl resin composition or a rubber solution can be sprayed over the interior of the container up to the open end thereof and sprayed in the interior of the bulkhead that is not applied as yet. After the spraying operation the last bulkhead is put in place and fastened down by means of the bolts 33. One of the panels 13 is provided with a filling inlet 36 which may be suitably valved in a manner not shown so as to permit filling and emptying of the container.

Once the container has been used and emptied it is a simple matter to reduce it to its component parts by releasing the bolts 33 and separating the bulkheads, the panels and the channels from each other. This permits the several parts to be stacked and transported in the most economical way. Reassembly can be accomplished at any time and any part of the container can be replaced in the event of damage without loss of undamaged sections. Also, the container can be kept tight at all times by means of the turnbuckles 29 and 30 and the bolts 33 regardless of shrinkage that may be encountered due to changes in weather conditions.

From the foregoing description it is believed that the construction of the container and the advantages of the improvements therein will be readily apparent to those skilled in this art.

Having thus described my invention, what I claim as new and desire to secure by Letters Patent is:

1. A container which is capable of being shipped in knocked down condition, then set up and used and subsequently broken down into its component parts for further shipping and use, said container comprising two bulkheads, each having means thereon providing a plurality of inwardly facing shoulders against which body panels may be placed and thereby prevented from moving outward, a plurality of connecting members extend-

ing between said bulkheads, each member comprising an inner channel forming strip, an outer channel forming strip having a U-shaped mid-section with wing portions extending outwardly, the two strips being secured together to provide oppositely facing channels, body panels mounted in said channels, bulkhead fastening members removably seated in the U-shaped mid-sections of said outer channel strip, and means cooperating with said fastening members to hold the bulkheads in place.

2. A container which is capable of being shipped in knocked down condition, then set up and used and subsequently broken down into its component parts for further shipping and use, said container comprising two bulkheads, a plurality of connecting members extending between said bulkheads, each member comprising an inner channel forming strip, an outer channel forming strip having a U-shaped mid-section with wing portions extending outwardly, the two strips being secured together to provide oppositely facing channels, body panels mounted in said channels, bulkhead fastening members removably seated in the U-shaped mid-sections of said outer channel strip, and means cooperating with said fastening members to hold the bulkheads in place.

3. A container which is capable of being shipped in knocked down condition, then set up and used and subsequently broken down into its component parts for further shipping and use, said container comprising two bulkheads, a plurality of connecting members extending between said bulkheads, each member comprising an inner channel forming strip, an outer channel forming strip having a U-shaped mid-section with wing portions extending outwardly, the two strips being secured together to provide oppositely facing channels, body panels mounted in said channels, bulkhead fastening members removably seated in the U-shaped mid-sections of said outer channel strip, and means cooperating with said fastening members to hold the bulkheads in place, said bulkhead fastening members comprising bolt lugs mounted in the U-shaped mid-sections at both ends of the connecting members, and bolts securing the bulkheads to the bolt lugs.

4. A container which is capable of being shipped in knocked down condition, then set up and used and subsequently broken down into its component parts for further shipping and use, said container comprising two bulkheads, a plurality of connecting members extending between said bulkheads, each member comprising an inner channel forming strip, an outer channel forming strip having a U-shaped mid-section with wing portions extending outwardly, the two strips being secured together to provide oppositely facing channels, body panels mounted in said channels, bulkhead fastening members removably seated in the U-shaped mid-sections of said outer channel strip, and means cooperating with said fastening members to hold the bulkheads in place, said bulkhead fastening members comprising U-shaped strips inserted in the U-shaped mid-sections at the ends of the connecting members, removable pins passing through the U-shaped strips and mid-sections and held in place by the panels, and bolts securing the bulkheads to the U-shaped strips.

PERCY H. WALLER,
EDWARD B. NOTTINGHAM.
